United States Patent Office

Des. 193,363

Patented Aug. 7, 1962

193,363

CLOSURE CAP

George J. Foss and Daniel D. Acton, Lancaster, Ohio, assignors to Anchor Hocking Glass Corporation, Lancaster, Ohio, a corporation of Delaware

Filed Dec. 1, 1960, Ser. No. 63,065

Term of patent 14 years

(Cl. D58—26)

FIG. 1 is a perspective view of a closure cap, showing our new design;

FIG. 2 is a top plan view thereof;

FIG. 3 is a bottom plan view thereof;

FIG. 4 is a side elevational view thereof;

FIG. 5 is an enlarged sectional view taken along line 5—5 of FIG. 2; and

FIG. 6 is an enlarged sectional view taken along line 6—6 of FIG. 2.

We claim:

The ornamental design for a closure cap, substantially as shown.

References Cited in the file of this patent

UNITED STATES PATENTS

D. 57,049	Ingram et al.	Feb. 1, 1921
D. 80,408	Burke	Jan. 28, 1930
D. 188,771	Chaplin	Sept. 6, 1960
2,484,039	Krueger	Oct. 11, 1949